UNITED STATES PATENT OFFICE.

VICTOR A. HALLQVIST AND GUSTAF E. WENNERBERG, OF BOSTON, MASSACHUSETTS.

SOFA-BED.

SPECIFICATION forming part of Letters Patent No. 453,474, dated June 2, 1891.

Application filed December 15, 1890. Serial No. 374,681. (No model.)

To all whom it may concern:

Be it known that we, VICTOR A. HALLQVIST and GUSTAF E. WENNERBERG, both citizens of Sweden, and residents of Boston, in the county of Suffolk and State of Massachusetts, have jointly invented new and useful Improvements in Sofa-Beds, of which the following, taken in connection with the accompanying drawings, is a specification.

10 This invention relates to improvements in sofa-beds, and it is carried out as follows, reference being had to the accompanying drawings, wherein—

Figure 1 represents a front perspective view of the invention shown in use as a sofa. Fig. 2 represents a plan view of the same shown in position as a bed. Fig. 3 represents a cross-section of Fig. 2. Fig. 4 represents a detail sectional view of a part of the bed-frame and one of its hinged sides and the brace for holding said parts in their relative positions when the device is used as a bed. Fig. 5 represents a transverse section of the frame-work, and showing in dotted lines the seat folded together when used as a sofa. Fig. 6 represents a similar transverse section, showing in dotted lines the seat turned over and expanded when used as a bed; and Fig. 7 represents a cross-section on the line X X, shown in Fig. 2.

Similar letters refer to similar parts wherever they occur on the different parts of the drawings.

The sofa-frame is composed of a back board A and ends B B, which are secured together in a suitable manner.

C is a brace connecting the lower front corners of the ends B B.

B' B' are arm-rests, as usual, preferably secured to the ends B B, as shown in the drawings.

D is the hollow or skeleton seat-frame, provided at each of its two opposite ends with three rigidly-attached trunnions or pins, or pins provided with rolls d, d' and d'', adapted to be guided in grooves on the interior of the ends B B. Each of such ends B has for this purpose a semicircular (or nearly so) groove b, having an open mouth b' at its front upper portion, as shown in Figs. 5 and 6, and having its rear upper end terminating as a hori-

zontal groove b''. In a line with the horizontal groove b'' is a horizontal groove b³, having upwardly-curved or segmental throats or openings b⁴ and b⁵ at its respective rear and forward ends, as shown in said Figs. 5 and 6.

When the device is used as a sofa, the seat-frame is in position as shown in Fig. 5, in which position the pin d is resting in the rear portion of the horizontal groove b'', the pin d' is resting in the rear end of the groove b³, and the pin d'' is resting in the middle part of the said groove b³, or nearly so, as shown in Fig. 5.

When it is desired to use the device as a bed, the seat-frame D is drawn forward until the pin d enters the rear upper end of the curved groove b and the pin d'' enters the throat b⁵, when the seat-frame D may be swung half a revolution on the pin d', resting in the groove b³ in the direction of the arrow shown in Fig. 5, causing the pin d to be guided through the semicircular groove b to its front open end or mouth b', and causing the pin d'' to be moved out of the throat b⁵ and to enter the throat b⁴, after which the bed-frame D is drawn forward to the position shown in Figs. 2, 3, and 5, leaving the pin d'' about midway in the groove b³, the pin d' in the forward end of said groove, and the pin d in front of and entirely outside of the mouth of the groove b, as fully shown in Fig. 6.

To the under sides of the seat-frame D are pivoted at e e the bed leaves or extensions E E, having secured to their outer edges the wire or canvas mattress F, as shown in Figs. 2, 3, 4, and 6.

f f f are suitable coiled springs interposed between the seat-frame D and mattress F, as shown in Figs. 2, 3, and 4.

E' E' are suitable legs or supports, preferably pivoted to the outside of the hinged leaves E E, which legs serve as firm supports for the leaves E E when the latter are swung outward and the device used as a bed, as shown in Figs. 2, 3, 4, and 6. For the purpose of holding the leaves E E in the expanded position shown in Figs. 2, 3, 4, and 6, and also for the purpose of properly stretching and holding the mattress F in position while the device is used as a bed, we pivot to each end of the leaves E a preferably curved metal

rod G, (shown in detail in Fig. 4,) which is guided in a perforated bracket or locking-piece g, secured in a suitable manner to the end piece D' of the seat-frame D. The rod G has near its upper end a locking projection G', adapted to be held against the bracket g, by the influence of a yielding spring G'', when the leaf E is swung outward and the mattress F expanded, as shown in Fig. 4.

10 When it is desired to close the bed, the spring G'' on the rod G is compressed, by which the projection G' is released from contact with the outside of the bracket g, thus permitting the rod G to pass freely through the said perforated bracket as the leaf E is being closed, and after being closed it may be locked in position to the seat-frame D by means of hooks h or other suitable or equivalent locking device.

20 In connection with this our improved sofa-bed we prefer to use a folding pillow-support at one end of the bed, as is shown in Figs. 2 and 3. Said pillow-support consists of a metal frame K of suitable length and width, the lower part of which is pivoted, preferably, to brackets D'' D'', secured to one of the ends D' of the seat-frame D, and in said brackets the said pillow-support K is also longitudinally adjustable. To one end of said pillow-supporting frame K is pivoted a similar frame k, which when in use is swung to the position shown in Figs. 2 and 3. When not in use, the frame k is folded over the frame K and the latter moved in its brackets until 35 it may be folded on top of the mattress F.

To change the bed into a sofa it is only necessary to swing the sides E E upward against the ends D' D' and to lock them in such positions. The seat-frame D is then 40 pushed inward sufficiently to cause the pin d to enter the mouth b' of the groove b and the pin d'' to enter the throat b⁴, after which the frame D is swung half a revolution on the pin d' as a pivot in the direction of arrow shown 45 in Fig. 6, causing the pin d to enter the groove b'' and the pin d'' to enter the throat b⁵ and the forward end of the groove b³, after which the frame D is pushed backward to the position shown in Fig. 5. A' is the back-support 50 of the sofa, as usual.

Having thus fully described the nature, construction, and operation of our invention, we wish to secure by Letters Patent and claim—

55 1. In a sofa-bed, the end frames B, each pro-

vided with a semicircular groove b, terminating at one end in an open mouth b' and at the opposite end in a horizontal groove b'', and a horizontal groove b''', arranged above the semicircular groove and provided at its opposite ends with the segmental grooves b⁴ b⁵, in combination with the reversible seat-frame provided with three rigidly-attached trunnions d d' d'', one of which is arranged to travel in the semicircular groove and its horizontal end portion, and the other two arranged to travel in the horizontal groove having the segmental end grooves for the purpose of reversing the seat-frame and extending it in front of the end frames, substantially as described.

2. In a sofa-bed, the combination, with the grooved end frames B, of the reversible and extensible seat-frame D, having trunnions engaging the grooves of the end frames, and provided at its inner and outer longitudinal edges with hinged leaves E, a spring-mattress F, attached to said leaves, and braces G, provided with locking devices for holding the leaves expanded and stretching the wire mattress, substantially as described.

3. In a sofa-bed, the combination, with the grooved end frames B, of the reversible and extensible seat-frame D, having trunnions engaging the ends of the end frames and provided at its inner and outer longitudinal edges with hinged leaves E, the wire mattress F, attached to said hinged leaves, the braces G, having locking-springs for holding the hinged leaves expanded and stretching the wire mattress, and legs E', hinged to the leaves for supporting the latter in their expanded position, substantially as described.

4. In a sofa-bed, the combination, with the seat-frames, of a longitudinally-sliding pillow-frame K, having a movable pivoted connection with one end of the seat-frame, and the supplemental pillow-supporting frame k, pivoted to one end of the longitudinally-sliding pillow-frame, substantially as described.

In testimony whereof we have signed our names to this specification, in the presence of two subscribing witnesses, on this 28th day of November, A. D. 1890.

VICTOR A. HALLQVIST.
GUSTAF E. WENNBERG.
